GARBAGE CAN LID RETAINER

Porter H. Moulds, Flushing, Mich.

Application August 14, 1934, Serial No. 739,773

2 Claims. (Cl. 220—57)

This invention relates to lids and fasteners therefor especially adapted for garbage cans and similar containers and has for the primary object the provision of a device of this character which will be self-locking to the can when applied thereto for preventing dogs and other animals from opening the can and dumping the contents and is so constructed that simple manual actuation is only needed to remove the lid from the can.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a can or container with a lid applied thereto and equipped with a self-locking fastener, said lid and fastener forming the subject matter of the present invention.

Figure 2 is a bottom plan view of the lid showing the fastener.

Referring in detail to the drawing, the numeral 1 indicates a container having a bead 2 about the mouth thereof. The can 1 is closed by a removable cover 3 of the flanged type and equipped centrally thereof with a handle 4 to facilitate the applying and removing of the lid from the can. The lid or cover 3 is provided with diametrically opposed offsets 5 in the flange thereof to form pockets 6. Brackets 7 are secured to the inner face of the lid and slidably support bars 8, the outer ends of which are in the form of hooks 9 receivable within the pockets 6. Pins 10 are secured to the bars and interposed between said pins and the brackets upon the bars are coil springs 11 acting to urge the bars in the direction of each other to bring the hooks 9 in engagement with the bead 2 of the can and thereby effectively secure the lid to the can against accidental displacement.

A guard 12 is secured to the inner face of the lid and slidably supports the bars and the latter have their opposing ends beveled, as shown at 13, to be engaged by a wedge-shaped element 14 secured to a plunger 15. The plunger and

wedge-shaped element 14 slide within a housing 16 secured to the cover and said cover also extends through an opening in the handle 4 and has secured to its outer end a finger piece 17. A person grasping the handle 4 may readily press the plunger 15 inwardly and due to the wedge-shaped element 14 the bars will be moved against the action of the springs disengaging the hooks 9 from the bead of the can, said hooks moving into the pockets 6 so that the lid may be readily lifted from the can. As soon as pressure is released from the plunger 15, the bars are returned to their initial position by the influence of the springs 11, being limited in their endwise movement towards each other by the tapered end of 15 the wedge-shaped element 14. The lid then may be positioned on the can and with a light pressure applied thereto the hooks 9 will snap over the bead and again firmly secure the lid to the can.

Having described the invention, I claim:

1. In combination with an open can having a bead about its opening, a flanged lid to close the open can, oppositely extending bars slidably supported to the lid and having hook-shaped ends to engage with the bead, spring means urging the bars in a direction to engage the hook-shaped ends thereof with the bead, a plunger slidably supported by the lid and having a wedge-shaped portion to engage the adjacent ends of said bar, a handle secured to the lid and having an opening to slidably receive the plunger, said lid having offsets to form pockets for receiving the hook-shaped ends of said bars.

2. In combination with an open can having a bead about its opening, a flanged lid to close the open can, oppositely extending bars slidably supported to the lid and having hook-shaped ends to engage with the bead, spring means urging the bars in a direction to engage the hook-shaped ends thereof with the bead, a plunger slidably supported by the lid and having a wedge-shaped portion to engage the adjacent ends of said bar, a handle secured to the lid and having an opening to slidably receive the plunger, said lid having offsets to form pockets for receiving the hook-shaped ends of said bars, and a guard secured to the lid and slidably supporting the bars.

PORTER H. MOULDS.
